[57] **CLAIM**

The ornamental design for a fishing reel housing, as shown and described.

DESCRIPTION

FIG. 1 is a top, left perspective view of a fishing reel housing showing our new design;

FIG. 2 is a left elevational view thereof;

FIG. 3 is a right elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of environment in FIGS. 1-5 and 7 is for illustrative purposes only and forms no part of the claimed design.
